(57) **CLAIM**

The ornamental design for an end cap for a table leg, as shown and described.

DESCRIPTION

FIG. 1 is a perspective view of an exemplary embodiment of an end cap for a table leg;

FIG. 2 is a front view of the end cap for a table leg, with the rear view being a mirror image thereof;

FIG. 3 is a top view of the end cap for a table leg;

FIG. 4 is a bottom view of the end cap for a table leg;

FIG. 5 is a left side view of the end cap for a table leg; and, FIG. 6 is a right side view of the end cap for a table leg. The broken lines shown in the figures are for illustrative purposes only and form no part of the claimed design.
